DESIGN FOR A CHAIR

Guy Stoddard, Twin Falls, Idaho

Application September 25, 1936, Serial No. 65,004

Term of patent 14 years

To all whom it may concern:

Be it known that I, Guy Stoddard, a citizen of the United States, residing at Twin Falls, in the county of Twin Falls and State of Idaho, have invented a new, original, and ornamental Design for a Chair, of which the following is a specification, reference being had to the accompanying drawing, forming part thereof.

Figure 1 is a perspective view of the chair, looking toward the front and showing my new design.

Figure 2 is a perspective view of the chair looking toward the rear and showing my new design.

Figure 3 is a perspective view of the chair looking toward one side thereof and showing my new design.

I claim:

The ornamental design for a chair, as shown.

GUY STODDARD.
